UNITED STATES PATENT OFFICE.

JACOB RUESCH, OF MILWAUKEE, WISCONSIN.

PRINTER'S QUOIN.

SPECIFICATION forming part of Letters Patent No. 763,637, dated June 28, 1904.

Application filed December 7, 1903. Serial No. 184,066. (No model.)

To all whom it may concern:

Be it known that I, JACOB RUESCH, a citizen of the United States, residing at Milwaukee, in the county of Milwaukee and State of 5 Wisconsin, have invented certain new and useful Improvements in Printers' Quoins, of which the following is a specification, reference being had to the accompanying drawings, forming a part thereof.

10 This invention relates more particularly to means for locking the wedge-sections of printer's quoins to each other after they have been tightened in the forms.

15 The object of the invention is to prevent the slipping of the furniture and the accidental unlocking of the type in a printer's form.

It consists of a locking device applied to a printer's quoins, as hereinafter particularly described, and defined in the appended claims.

20 In the accompanying drawings like letters designate the same parts in both figures.

Figure 1 is a plan view of a printer's quoins to which my locking device is applied, parts of the quoins-sections being broken away and 25 shown in section; and Fig. 2 is a perspective view of the quoins, with the key used to tighten the quoins in a form.

The quoins to which my locking device is adapted and applied is composed of two wedge-shaped sections *a* and *b*, formed on their opposing faces with interworking longitudinal tongues *c* and *d* and grooves *e* and *f* for guiding and holding said sections in the proper relation to each other. The sections are also 30 formed on each side of the tongues *c* and *d* with opposing racks *g* for moving them longitudinally one upon the other with a key 35 *h* and spreading and tightening the quoins in a form according to the usual practice in 40 locking a type-form in a chase with quoins of this class. The tongue *d* on one section is serrated or formed with a longitudinal series of teeth *i*, and the other section is provided with a toothed eccentric *j*, pivoted on a pin *k* 45 in a transverse recess in the larger end of said section. The eccentric is provided with a pin or finger-piece *l* for moving it into and out of engagement with the teeth *i* on the opposing section.

50 In operation when the quoins has been suf-

ficiently spread with the key *h* to bind and hold the form in place in the chase the eccentric *j* is turned and pressed against the toothed tongue *d* of the opposing section and one section is moved slightly in advance on the other 55 section with the key till the teeth of the eccentric, which is still pressed against the teeth *i* on the opposing section, drop into engagement therewith, thus locking the two sections together against backward movement. 60 To unlock the form, the key *h* is inserted in the opposing racks *g*, one section is advanced slightly upon the other to release the teeth of the eccentric *j* from the teeth of the tongue *d*, and the eccentric is then turned, by means 65 of the pin or finger-piece *l*, out of engagement with the toothed tongue *d*. The sections are now free to move backward one upon the other and can be so moved in the usual way with the key *h*.

70 When the eccentric is engaged, as shown in Fig. 1, with the toothed tongue *d* on the opposing section, any tendency of the furniture to slip and crowd one section backward upon the other is resisted by said eccentric, which 75 tends under such conditions to spread or separate the sections transversely, as indicated by dotted lines on Fig. 1, and thereby lock the form still tighter. In case the form becomes loosened after it has been locked the 80 key can be inserted in the opposing racks *g* and one section advanced upon the other till the slack or play in the form is taken up, whereupon the eccentric will be reengaged with the toothed tongue on the opposing section, as above explained.

Modifications in the details of construction may be made without departing from the principle and intended scope of the invention.

I claim—

1. A printer's quoins composed of two wedge-shaped sections, one of which is provided with a longitudinal series of teeth and the other with a toothed eccentric adapted to be engaged with the teeth on the first section and by its rotation, when so engaged, to separate said sections transversely when one of them is moved longitudinally backward with relation to the other, substantially as described.

2. A printer's quoins composed of two wedge-

90

95

100

- shaped sections provided with interworking longitudinal guiding tongues and grooves, and with opposing racks for tightening the sections with a key in a form, the tongue on 5 one section being serrated and the other section provided with a toothed eccentric adapted to be engaged with said serrated tongue and by its rotation, when so engaged, to separate said sections transversely when one of 10 them is moved longitudinally backward with relation to the other, substantially as described.
3. A printer's quoins composed of two wedge-shaped sections, one of which is provided with 15 a longitudinal series of teeth and the other with

a toothed eccentric provided with a pin which projects therefrom on opposite sides and adapted to be engaged with the teeth on the first section and by its rotation, when so engaged, to separate said sections transversely 20 when one of them is moved longitudinally backward with relation to the other, substantially as described.

In witness whereof I hereto affix my signature in presence of two witnesses.

JACOB RUESCH.
